PRODUCTION OF ACRYLIC ACID AND ITS SALTS

Walter Reppe, Franz Reicheneder, and Guenther Stengel, Ludwigshafen (Rhine), and Albert Zieger, Heidelberg, Germany, assignors to Badische Anilin- & Soda-Fabrik Aktiengesellschaft, Ludwigshafen (Rhine), Germany

Application February 15, 1957, Serial No. 641,002

2 Claims. (Cl. 260—533)

This invention relates to a process for the production of acrylic acid or its salts by the reaction of acetylene, carbon monoxide and water at high pressures.

It is already known to prepare acrylic acid or its salts by the reaction of acetylene with carbon monoxide and water in the presence of carbonyl-forming metals or their compounds. Derivatives of nickel, preferably nickel halides, have proved especially suitable as catalysts. The co-employment of organic solvents is recommended because these effect an increase in the concentration of acetylene and carbon monoxide in the reaction liquid.

As a rule in the said reactions there are used gas mixtures of equal parts of carbon monoxide and acetylene and operation is under increased pressure in order to increase the space-time yields. Since mixtures of acetylene and carbon monoxide in the ratio of about 1:1 can decompose under increased pressure with the evolution of large amounts of heat, expensive safety precautions are necessary to avoid explosions or detonations.

It has already been proposed to react mixtures of acetylene and carbon monoxide which have a lower proportion of acetylene at pressures above 50 atmospheres in the presence of carbonyl-forming metals and at temperatures below 120° C. to form esters, including acrylic acid esters, but the yields of acrylic acid esters and the space-time yields are not satisfactory.

The object of the present invention is to provide an improved process for the production of acrylic acid or acrylic acid salts. A further object is to provide a process in which acetylene, carbon monoxide and water can be reacted to acrylic acid in good space-time yields. A further object is to provide a process which in spite of the use of high pressures does not necessitate any special safety precautions for working with acetylene. Other objects and advantages of the invention will be evident from the detailed description.

We have now found, contrary to expectation, that these objects can be accomplished and acrylic acid or its salts can be prepared in a more suitable manner from acetylene, carbon monoxide and water by carrying out this reaction at a minimum total pressure of 75 atmospheres (absolute) and below the limiting decomposition pressure with a mixture of acetylene and carbon monoxide at temperatures above 180° C. The preferred reaction temperatures lie between 220° and 300° C.

The decomposition limiting pressure of mixtures of acetylene and carbon monoxide is dependent on the composition of the gas mixture. The accompanying drawing shows a diagram for the course of the decomposition limiting pressure in dependence on the composition of the gas mixture consisting of acetylene and carbon monoxide. To the ordinates are applied the acetylene content of the mixture in percent by volume and to the abscissae the total pressure in absolute atmospheres on a logarithmic scale. Small circles represent measurement points at which no decomposition of the mixture occurs upon ignition. The crosses correspond to measurement points at which decomposition reactions occur.

2

Thus the region in which no decomposition reactions take place lies below the curve.

The decomposition limiting pressure is determined in a stainless steel tube 1.20 meters in length and having an internal diameter of 90 millimeters. The mixture is ignited with a sparking plug heated by a platinum wire to the melting point of platinum (more detailed information regarding the determination of the decomposition limiting pressure will be found in the book by Walter Reppe, "Chemie und Technik der Acetylen-Druck-Reaktionen," Verlag Chemie (1951), pages 1 to 19).

As may be seen from the diagram, it is possible according to this invention, at pressures of 200 or 300 absolute atmospheres, to use gas mixtures which contain up to 23 or 20% by volume of acetylene.

The decomposition limiting pressure is as a rule somewhat reduced by the water so that operation without danger is ensured if the limiting decomposition pressure of the gas mixture consisting only of acetylene and carbon monoxide is not overstepped.

An advantage of the present process may be seen in the fact that special safety precautions are superfluous in carrying out reactions which are attributable to the ready decomposability of acetylene. Moreover with the high total pressure of the system, the partial pressure of the acetylene is also high in spite of the relatively small acetylene content, so that the process is characterized by good space-time yields. In this process it is preferred to use mixtures of acetylene and carbon monoxide which have acetylene contents between 10 and 23% by volume, these data holding good for the gas mixtures consisting only of acetylene and carbon monoxide. It is obvious that part of the carbon monoxide may be replaced by indifferent gases, such as nitrogen, but the partial pressure of the carbon monoxide is thereby reduced.

As catalysts in this process there may be used nickel salts. The nickel salts of weak acids are especially suitable, as for example the nickel salts of acetic acid, propionic acid and higher saturated monocarboxylic acids. Salts of unsaturated carboxylic acids, as for example acrylic acid, or of polycarboxylic acids, such as succinic acid, adipic acid, tartaric acid or phthalic acid, may however also be used. Complex alkali nickel cyanides, preferably potassium or sodium nickel cyanides, have also been found to be suitable. These complex alkali cyanide catalysts may be formed from a nickel salt and an alkali cyanide in the reaction chamber. They may however also be previously prepared from their components. Since the complex nickel alkali cyanides have a good solubility in water, no troublesome deposits are formed in the reaction apparatus. An addition of alkaline agents, preferably alkali carbonates, such as sodium or potassium carbonate, to the reaction mixture is of interest. Such an amount of alkali may be added that the whole of the acrylic acid formed is obtained as salt, or the addition of the said agent may be so chosen that it neutralizes only a part of the acrylic acid formed. As a rule, the synthesis of acrylic acid is carried out in the absence of indifferent organic solvents. The concentration of nickel ions in the liquid reaction medium should preferably lie between 0.05 and 1.0% by weight.

As the enumeration of some examples of effective catalysts shows, the peculiarity of the present invention does not reside in the discovery of special catalysts, but on the other hand the invention consists in the use of physically determined process conditions in the synthesis of acrylic acid.

Although the addition of activators to increase the activity of the catalysts, for example the addition of cuprous salts, is not excluded from the present process, as a rule the addition of activators can be dispensed with

because satisfactory space-time yields are also obtained in the absence of activators.

The process may be carried out discontinuously or continuously. The carbon monoxide used in excess can be partly or wholly decompressed and, after the addition of acetylene or mixtures rich in acetylene, can be recompressed to the reaction pressure and supplied to the reaction chamber.

The following examples will further illustrate this invention but the invention is not restricted to these examples.

Example 1

400 ccs. of a solution having the following composition:

3400 grams of water
46.7 grams of nickel sulfate ($\text{NiSO}_4 \cdot 7\text{H}_2\text{O}$)
60 grams of potassium cyanide and
387 grams of anhydrous sodium carbonate

are pumped per hour upwardly through a vertically-arranged stainless steel tube capable of withstanding high pressure which has a capacity of 1 liter. At the same time a gas mixture of 17% by volume of acetylene and 83% by volume of carbon monoxide is led through the tube under 200 atmospheres absolute. The reaction temperature is adjusted to 245° to 250° C. by electrical heating. 700 liters of gas, mainly consisting of carbon monoxide, are released from pressure per hour. Each day 9.6 liters of water containing catalyst are charged into the tube and 13.5 to 14.5 liters of product recovered from which the acrylic acid is isolated in the usual way. An average of 5 to 6 kilograms of pure acrylic acid are obtained from the daily product by distillation.

Example 2

A solution of 41 grams of nickel sulfate ($\text{NiSO}_4 \cdot 7\text{H}_2\text{O}$) and 45 grams of sodium cyanide in 4500 grams of water is pumped through the same arrangement as in Example 1. At the same time a gas mixture of 19% by volume of acetylene and 81% by volume of carbon monoxide is led through the tube at 200 atmospheres absolute. The reaction temperature is adjusted to 260° to 270° C. by electrical heating. 1000 to 1200 liters of gas per hour are released from pressure. Each day 24.0 liters of catalyst solution are charged into the tube and 30 liters of product recovered from which up to 10 kilograms of acrylic acid can be isolated in the usual way.

Example 3

10 liters of a solution of 400 grams of nickel acetate in 58 liters of water are pumped upwardly each hour through a vertically-arranged stainless steel tube of 3 liters' capacity which is capable of withstanding high pressure. At the same time a gas mixture of 20% of acetylene and 80% of carbon monoxide is led through the tube under 200 atmospheres absolute. The reaction temperature is kept at 280° to 290° C. by electrical heating. Each hour 6000 liters of gas consisting mainly of a mixture of carbon monoxide and acetylene with 13% of acetylene are released from pressure. The decompressed gas can be led into the reaction vessel again after the admixture therewith of acetylene. Each day 240 liters of water containing catalyst are charged into the tube. From a product of about 270 liters per day, about 46 kilograms of acrylic acid can be isolated by distillation.

Example 4

A nickel acrylate solution which contains 1.8 grams of nickel to one liter of solution is pumped through a three liter vertical high-pressure container of stainless steel from bottom to top at a rate of 10 liters per hour. At the same time a gas mixture of 20% by volume of acetylene and 80% by volume of carbon monoxide is fed in

from the bottom at a pressure of 200 atmospheres Hg. 7 cubic meters (NTP) of a gas mixture which still contains 15% of acetylene are expanded per hour through the container head. Another 4 cubic meters (NTP) of this gas are refed into the container as a cycle gas from below by means of a gas pump at a pressure of 200 atmospheres. The expanded gas, the acetylene content thereof having been raised to 20%, can be recycled for further reaction.

The reaction temperature is set to 280° to 290° C. by electric heating.

The amount of catalyst solution pumped into the container is 240 liters per day. The output amounts to 275 liters from which 48 kilograms of acrylic acid are isolated.

Example 5

A solution of nickel adipate which contains 1.8 grams of nickel to one liter is pumped through a container of the type described in Example 4 together with a gas mixture of 20% by volume of acetylene and 80% by volume of carbon monoxide which is fed in at a pressure of 200 atmospheres Hg. The reaction temperature is set to 280° to 290° C. The quantity of gas expanded amounts to 1.200 to 1.500 liters per hour. With 19.2 liters of catalyst solution put in per day 22.7 liters of output were obtained from which 7.5 kilograms of acrylic acid can be isolated per day.

Example 6

Using a container of the type described in Example 4 a solution of nickel citrate containing 1.8 grams of nickel to one liter is fed in at a rate of 19.2 liters per day. The output of the reaction amounts to 21.8 liters per day from which 7.0 kilograms of pure acrylic acid can be isolated.

Example 7

With the container being the same as in Example 4 a solution of nickel sulfate which contains 1.8 grams of nickel is fed in at a rate of 19.5 liters per day. From the output of 22.3 liters per day 5.5 kilograms of pure acrylic acid can be isolated.

We claim:

1. In a process for the production of an acrylic compound selected from the group consisting of free acrylic acid and its alkali metal salts by the interaction of acetylene, carbon monoxide and water in the presence of a nickel compound as carbonylation catalyst, the improvement which comprises carrying out said reaction at a minimum pressure of 75 atmospheres absolute but below the decomposition limiting pressure of the mixture of acetylene and carbon monoxide at a temperature between 180° and 300° C.
2. In a process for the production of an acrylic compound selected from the group consisting of free acrylic acid and its alkali metal salts by the interaction of acetylene, carbon monoxide and water in the presence of a nickel compound as carbonylation catalyst, the improvement which comprises carrying out said reaction at a minimum pressure of 75 atmospheres absolute but below the decomposition limiting pressure of a mixture of acetylene and carbon monoxide containing between 10 and 23% by volume of acetylene at a temperature between 220° and 300° C.
